UNITED STATES PATENT OFFICE.

LOUIS E. WOOD, OF FARRELL, PENNSYLVANIA.

CURTAIN-STRETCHER.

1,351,274.

Specification of Letters Patent. Patented Aug. 31, 1920.

Application filed May 24, 1920. Serial No. 383,840.

To all whom it may concern:

Be it known that I, LOUIS E. WOOD, a citizen of the United States, residing at Farrell, in the county of Mercer and State of Pennsylvania, have invented certain new and useful Improvements in Curtain-Stretchers; and I do declare the following to be a full, clear, and exact description of the invention, such as will enable others skilled in the art to which it appertains to make and use the same.

This invention relates to an improved curtain stretcher and one object of the invention is to provide a curtain stretcher so constructed that the body portion thereof may be rotatably mounted thus permitting the body portion to be turned to bring portions of the curtain into position for drying to the best advantage and also to permit the curtains to be easily connected with the stretcher.

Another object of the invention is to so construct this stretcher that it can be readily adjusted according to the size and shape of the curtain to be stretched and dried.

Another object of the invention is to so construct this stretcher that the curtain may be evenly stretched and thus the curtain prevented from being pulled out of shape.

Another object of the invention is to so construct this stretcher that the lower head may be easily and quickly drawn downwardly to stretch a curtain and the lower head then securely but releasably held in the set position upon the standard of the drive.

Another object of the invention is to so mount the vertical rods or arms of the stretcher that they may be removed when desired, thus making it only necessary to put as many rods in place when using the stretcher as the length of the curtain to be stretched and dried requires.

Another object of the invention is to so construct this stretcher that it may be taken apart and thus permitted to be stored in a small amount of space or easily carried from one place to another.

This invention is illustrated in the accompanying drawings wherein

Figure 1 is a view in side elevation showing the stretcher with one of the vertical rods or arms in place and the stretcher in position for use.

Fig. 2 is a top plan view of the improved stretcher.

Fig. 3 is a fragmentary transverse sectional view taken along the line 3—3 of Fig. 1.

Fig. 4 is a fragmentary sectional view along the line 4—4 of Fig. 2.

Fig. 5 is a transverse sectional view taken along the line 5—5 of Fig. 1.

Fig. 6 is a fragmentary sectional view through the lower portion of the drier taken along the line 6—6 of Fig. 5 with certain portions of the drier shown in elevation.

Fig. 7 is a fragmentary perspective view of the upper head.

Fig. 8 is a perspective view of the upper end portion of one of the vertical curtain engaging rods.

Fig. 9 is a transverse sectional view through the standard and locking collar of the drum.

This curtain drier is provided with a rotatable body which is mounted upon a standard 1, which standard passes through the upper hub plate 2 of the base and rests in the socket 3 of the lower hub plate 4, thus rotatably mounting the standard. The supporting legs 5 of the base 1 are preferably provided with rollers 6 so that the drier may be easily moved from one place to another and have their inner ends extending between the upper and lower hub plates 2 and 4 and securely clamped between these plates by the bolt 7. It will thus be seen that when it is desired to store the drier the bolts 7 may be loosened and the supporting legs 90 withdrawn from between the hub plates.

The body of the drier is provided with an upper head indicated in general by the numeral 8 and a lower head indicated in general by the numeral 9. Each of these heads is provided with upper and lower hub plates 10 and 11 between which are the spokes 12 and these hub plates carry securing bolts 11' which may be tightened to securely but releasably hold the spokes in place. Side bars 13 are connected with the enlarged outer end portions 14 of the spokes 12 and these side bars terminate at the side edges of pockets 15 formed in the enlarged end portions of the spokes thus providing continuations of the pockets as clearly shown in Fig. 3 and also shown in Fig. 7. These side bars 13 are provided with outwardly extending shoulders 17 in which are formed notches 18 which will be positioned in staggered relation to the pins 16.

The curtains which are to be dried are to extend circumferentially of the body or drum and in order to support the curtains, there has been provided vertical rods or bars 5 19 which extend through the slots or pockets 15 and are provided at their upper ends with heads 20 which extend inwardly and are provided with transversely extending grooves 21 to receive the U-shaped clips 22 10 carried by the enlarged outer end portions of the spokes for the upper head. The inner ends of these heads 20 are curved as shown clearly in Fig. 8 so that the heads may be passed into the clips and the rods then 15 swung downwardly into the vertical position with the clips positioned in the notches 21 and the rods positioned in the pockets 15. It will thus be seen that when the rods are in place they will be carried by the 20 upper head and passed through the pockets of the lower head. This upper head fits upon the tapered upper end portion of the standard 1 and the lower head is slidably mounted upon the standard and has its 25 lower hub plate provided with a depending collar 23, which collar has one side portion cut out to provide a slot for receiving the clamping ring 24. The clamping ring 24 fits loosely upon the neck 23 and carries a 30 set screw 25 which will engage the neck and draw the collar transversely thereof into binding engagement with the standard. Therefore, the lower head of the drum can be securely but releasably clamped at a desired point upon the standard. 35

The lower head should be drawn downwardly after the curtains have been connected with the drier to stretch the curtains and in order to do so there has been provided a 40 lever 26 which is provided with side arms 27 extending upon opposite sides of the standard and pivotally connected with a bracket 28 which is loosely connected with one of the legs 5 of the base for pivotal movement. 45 A hook 29 extends upwardly from this lever 26 for engaging a chain 30, which chain has certain of its links engaging hooks 31 carried by the lower hub plate of the lower head. Therefore, when the lever has its 50 hook connected with the intermediate portion of the chain, the lever can be forced downwardly and the lower drum head will be drawn downwardly and the curtain evenly stretched at all points. After the 55 curtain has been stretched the desired amount, the set screw 25 will be tightened and the band or ring 24 will be drawn into binding engagement with the standard and thus releasably but securely hold the lower head at the desired point upon the drum to retain the curtain stretched.

When this device is in use it will be assembled as shown with the vertical rods extending through the pockets of the upper 60 and lower drums. Only one of the rods will

be provided with the pins 32 for engaging the curtain as the remaining rods are simply provided to support the curtain intermediate its length and permit it to be properly stretched longitudinally and transversely. 70 The curtain is to extend longitudinally about the circumference of the drum and in order to engage the second end portion of the curtain there has been provided a bar 33 which extends vertically of the drum and 75 is provided with pins 34 for engaging the curtain. This bar 33 is provided with a metal strip 35 which is secured to the edge of the bar and extends beyond the inner face thereof for fitting into selected notches 80 of the upper and lower side bars of the two drum heads. Clamping bolts 36 extend across the side bars and have their heads 37 engaging the inner faces of the side bars and have their outer end portions extending 85 through slots 38 of the bar 33 and threaded to carry securing nuts 39 so that the bar may be securely but releasably and adjustably connected with the drum. It will thus be seen that when the curtains are put in 90 place they will each have one end connected with the pins 32 of the anchoring rod 19 and will then be drawn circumferentially about the drum and connected with the pins of the bar 33. The upper side edge portion of the 95 curtain will be engaged by the pins 16 of the upper head and the lower side edge portion will be connected with the pins of the lower drum head. The lower drum head will then be drawn downwardly to the desired point and locate in the adjusted position. The chain will then be released from the hook 29 and the drum may rotate so that the sun may shine upon all portions of the curtain as the drum rotates or so that the drum may be turned to bring portions of the curtain toward a stove or other source of heat in case the curtains are being dried indoors. It will thus be seen that the drier may be adjusted according to the 100 size of the curtain and also may be adjusted according to whether a square or oblong curtain is being dried. After the curtains have been dried, the drier may be taken apart and put away in a comparatively 105 small amount of space until again needed.

I claim:

1. A curtain stretcher comprising a rotatably mounted standard, a drum having an upper curtain engaging head fitting upon the standard and a lower curtain engaging head slidably fitting upon the standard, vertical bars loosely connected with the upper head and slidably engaging the lower head, one bar being provided with curtain engaging means, a vertically extending curtain engaging bar releasably and slidably connected with the heads, and means for drawing the lower head downwardly to stretch a curtain connected with the heads and bars. 115

2. A curtain stretcher comprising a base, a standard rotatably carried by the base, a drum having an upper head, vertical bars and a lower head slidable upon the standard and slidably engaging the vertical bars, curtain engaging elements carried by the heads and certain of the bars, and means carried by the base for engagement with the lower head to draw the lower head downwardly 10 and stretch a curtain.

3. A curtain stretcher comprising a standard, a drum carried by the standard and having upper and lower curtain engaging heads and vertical curtain engaging bars bridging 15 the space between the heads, the lower head being slidably mounted upon the standard and slidably engaging the vertical bars, curtain engaging means carried by the heads and certain of the vertical bars, and means 20 for releasably securing the movable head in an adjusted position upon the standard.

4. A curtain stretcher comprising a standard, a drum carried by the standard and having upper and lower curtain engaging heads, one head being adjustable vertically 25 of the standard, curtain engaging bars bridging the space between the heads and curtain guiding and supporting bars bridging the space between the heads and positioned between the engaging bars, the heads 30 being provided with pockets for receiving the supporting bars and one of the engaging bars, and the bars being loosely connected with upper head and slidably engaging the 35 lower head.

5. The structure of claim 4 having the bars provided with inwardly extending heads at their upper ends and clips carried by the upper drum head and engaging the 40 heads of the bars to releasably and pivotally mount the bars.

6. A curtain stretcher comprising a standard, a drum carried by the standard and

having upper and lower curtain engaging heads, one head being adjustable vertically 45 of the standard, curtain engaging bars bridging the space between the heads and curtain guiding and supporting bars bridging the space between the heads and positioned between the engaging bars, the heads 50 being provided with notches cut vertically in their peripheral faces and one of the curtain engaging bars provided with a locking strip fitting into selected notches of the heads to hold the bar against movement circumferentially of the drum. 55

7. The structure of claim 6 having the bar provided with longitudinally extending slots, and clamps having stems extending through the slots and provided with heads 60 engaging the drum heads, and securing means carried by the stems and engaging the bar to releasably and adjustably hold the bar in engagement with the drum heads.

8. The structure of claim 2 having the 65 head moving means comprising a lever pivotally connected with the base and straddling the standard, engaging elements carried by the lower head upon opposite sides of the standard, an engaging element carried 70 by the lever, and a cable engaged by the engaging element of the lever and having its end portions carried upwardly and releasably engaged by the engaging elements of the drum head. 75

9. The structure of claim 3 having each drum head provided with a hub, spokes extending from the hub and having seats cut in their outer ends to receive vertical bars, and side bars connected with the spokes 80 upon opposite sides of the seats and provided with curtain engaging elements.

In testimony whereof I have hereunto set my hand.

LOUIS E. WOOD.
